UNITED STATES PATENT OFFICE.

CHARLES L. KAUFMAN, OF ENGLEWOOD, NEW JERSEY, ASSIGNOR TO ALEXANDER ARBIB, OF NEW YORK, N. Y.

APPARATUS FOR MAKING FEATHER BOAS AND THE LIKE.

1,170,820.

Specification of Letters Patent.

Patented Feb. 8, 1916.

Application filed January 5, 1914. Serial No. 810,391.

To all whom it may concern:

Be it known that I, CHARLES L. KAUFMAN, a citizen of the United States of America, and resident of Englewood, in the county 5 of Bergen and State of New Jersey, (whose post-office address is Englewood, New Jersey,) have invented certain new and useful Improvements in Apparatus for Making Feather Boas and the like, of which the following is a specification.

This invention relates broadly to apparatus for making feather boas and the like, and contemplates more particularly the provision of means adapted to present to a predetermined point, preferably adjacent a sewing or binding instrumentality, a substantially continuous line of appropriate material, thereat preferably to be bound together and transformed into a boa or the like.

A further object of this invention is to provide a device or devices adapted to maintain in a predetermined line of travel certain predetermined portions of the material or units of material, as, for instance, the flues and quills of feathers or the like.

Another object is to provide such a device or devices that the quills will be directed each to follow a predetermined line of travel, and also a device or devices adapted to grip or clasp the flues during movements of the units of material whereby said units will be prevented predeterminedly from having any relative movement one with reference to another.

Another object is to provide transporting means for the units of material whereby the units may be mounted thereon at a plurality of predeterminedly spaced locations.

A further object is to provide a plurality of independent instrumentalities each adapted predeterminedly to transport the units of material during a maintenance of the said units in predetermined adjustment with relation to each other, and in connection therewith an instrumentality whose function it is to transfer said units of material from one of said transportation instrumentalities to another.

Other objects and aims of this invention,

more or less broad than those stated above, 50 together with the advantages inherent, will be in part obvious and in part specifically referred to in the course of the following description of the elements, combinations, arrangements of parts, and applications of 55 principles constituting the invention; and the scope of protection contemplated will appear from the claims.

Referring now to the accompanying drawings which are to be taken as a part of this 60 specification and wherein are shown one of the various possible embodiments of my invention:—Figure 1 is a view in side elevation of said embodiment; Fig. 2 is a top plan view of the portion of the embodiment to the 65 right of the line 2—2 of Fig. 1 and disclosing certain of the parts shown in said Fig. 1; Fig. 3 is an enlarged detailed view disclosing certain of the parts shown in Figs. 1 and 2; Fig. 4 is a sectional view, taken on the 70 line 4—4 of Fig. 1; Fig. 5 is a sectional view, taken on the line 5—5 of Fig. 4; Fig. 6 is a sectional view, taken on the line 6—6 of Fig. 5; Fig. 7 is a detail perspective view on an enlarged scale, showing certain of the 75 parts also disclosed in Figs. 1, 2, 3, 4, 5 and 6; Fig. 8 is a top plan view, partly broken away of one of the parts shown in Fig. 7; Fig. 9 is a sectional view, taken on the line 9—9 of Fig. 8; Fig. 10 is a sectional view, 80 taken on the line 10—10 of Fig. 1; Fig. 11 is a sectional view, taken on the line 11—11 of Fig. 1; Fig. 12 is a detail perspective view, on an enlarged scale, showing certain 85 of the parts disclosed in Figs. 1, 4, 5, 7 and 8; Fig. 13 is a side elevation, on an enlarged scale, showing certain of the parts disclosed in Figs. 1, 4, 5 and 7; Fig. 14 is an end elevation of the parts shown in Fig. 13 and looking in the direction of the arrow 14; and 90 Fig. 15 is a detail view disclosing certain of the parts shown in Fig. 1 as they would appear if viewed as indicated by the arrow 15.

Similar reference characters refer to similar parts throughout the several views of the 95 drawings.

Now taking up particularly the description of the illustrative embodiment of this

invention disclosed in the drawings, it is preliminarily stated that the conveying means now about to be disclosed are illustrative merely, and are shown in more or less spaced apart and contacting relations, the characteristics of which, as well as the characteristics of the other individual elements and pluralities of elements, are not essential to the essence of the invention.

10 There is shown as extending transversely of Figs. 1 and 4 a main driving shaft 16, assumed to be preferably connected with suitable power. This shaft carries fixedly thereon a gear 17 and a crank 18. Within 15 table 19 is set, as best shown in Figs. 4 and 5, the bed-plate or lower casing 20 of a sewing machine of suitable type.

The sewing machine is driven by the gear 17 through the pinion 21 and the gear 22, 20 which last is suitably mounted upon the main drive-shaft of the sewing machine.

The gear 23 is driven intermittently during a continuous rotation of shaft 16, through these means, to wit, the crank 18, 25 the link 25, the lever 26 (which is loosely pivoted about the shaft 27), the pawl 28, and the ratchet 29. The gear 23 and the ratchet 29, as well as a sprocket-wheel 30 are preferably fixedly mounted upon the 30 shaft 27. A preferably flexible detent 36 is mounted upon table 19 and coöperates with ratchet 29 as shown in Fig. 4.

Sprocket-wheel 30, being thus intermittently driven, transmits, through the chain 35 24, an intermittent drive to the sprocket 31.

Gear 23 meshes with a gear 32 fixedly mounted on shaft 33, and gear 32 meshes with a gear 34, fixedly mounted on shaft 35.

Now of the gear 23, gear 32, sprocket- 40 wheel 31 and gear 34, mentioned in the next preceding three paragraphs, it may be stated, first, that the gear 23, through the pulley 37 fixedly connected thereto, intermittently drives the pair of belts 38; second, that the gear 32, through the pulley 39 fixedly connected thereto, similarly intermittently drives the pair of belts 40; third, that the sprocket-wheel 31, through the pulley 41 fixedly connected thereto, similarly intermittently drives the belt 42; and, 45 fourth, that the gear 34, through the roller 43, fixedly connected thereto, similarly intermittently drives the completed line of material 44 from the rear of the machine as shown in Fig. 1. From the design of the teeth shown (said Fig. 1) as being here carried by ratchet 29, it will be seen that simultaneously belts 40 are intermittently fed in the direction of the arrow 45 and belts 60 38 and 42 are intermittently fed in the direction of the arrow 46; these belts here coöperating as hereinafter described to transport a continuous line of units of material from about the point 47 (Fig. 1), 65 past the needle 48 of the sewing machine,

and toward what may be termed the two exit-rollers 43 and 49. This roller 49 has not previously been mentioned, but the same is provided with a smooth peripheral surface (*vide* Fig. 15) which bears resiliently, 7 due to the usual mounting therefor indicated at 50 in Fig. 1, against a similar peripheral surface provided on the roller 43 (*vide* Fig. 15).

At one end of the table 19 is located a 7 pulley 51, journaled in brackets 52 (shown in Fig. 5). This pulley is a guiding agent for the pair of belts 40; the belts being side-wisely spaced by the four spaced annular ribs carried by pulley 51 as best disclosed in 8 Fig. 3, the two inner ribs defining therebetween as shown a V-shaped annular groove 53. From pulley 51 the belts 40 run horizontally over table 19 as shown in Figs. 1, 4, 5 and 7, in close proximity to and in 8 superposition upon the horizontally extending lengths of each of the complementary pair of belts 38. And although hereinafter a detailed description of the operation of this type of apparatus will be entered into, 9 it may aid comprehension at this point to state that it is between the contacting surfaces of pairs of belts 40 and 38 that the line of material is gripped; after leaving the spiked belt 42, and transported toward 9 and beyond the sewing means, in such a manner that various alining and compressing instrumentalities hereinafter described will arrange such material in a preferable disposition as it approaches the sewing point 10 and also therebeyond. The belts 40 and 38, as well as the belt 42, along their respective horizontal lengths are adapted for simultaneous and similar travel in the direction of the arrow 46, due to the presence 10 of the driving and connecting instrumentalities described in the preceding paragraph. After passing over pulley 51, belts 40 next pass over the pulley 59, which is generally similar to pulley 51 (even preferably to the extent of being provided with a similar annular groove 53'), as best disclosed in Fig. 15, and thence pass over pulleys 54 as best disclosed in Fig. 1.

Pulleys 54, each revolubly mounted as 11 shown upon fixture 55, constitute with said fixture a conveniently adjustable instrumentality for a tightening or slackening of said belts 40. Fixture 55 is rotatively mounted upon a transverse rod 56, and is adjustable 12 upon said rod by means of the coöperation of the arcuate slot carried by said fixture with a clamp-nut or the like mounted upon the rod 57. Pulleys 54 carry between belts 40 an annular rib similar to that disclosed 12 in Fig. 15 as carried by pulley 38. In further aid of spacing these belts, fixture 55 carries a plate 58 which fixedly supports a plurality of spacing blocks similar to the blocks 59 supported by the U-shaped hanger 13

60 carried by brackets 52. The rod and blocks carried by these brackets 52 are best disclosed in Figs. 1 and 4. At this point attention may be called to one of the functions served by fixture 55, and this is, that when said fixture is swung on its rod 56, in a clockwise direction belts 40 will be sufficiently slackened to be readily disengaged from pulleys 55, to the end that the belts 40 0 may be swung out of the way and thereupon belts 38 may also be swung out of the way so that access to the sewing machine or other parts of the embodiment may conveniently be had. Now tracing the paths of travel 5 of the pair of belts 38, it will be seen that the belts pass over a pulley 37 similar (see Fig. 4) to the pulley 39 and fixedly carried by the shaft 27. From this pulley 37 the belts 38 are adapted to travel in the direction of the arrow 46 to pass over the pulley 61, mounted upon the shaft 62, and thence pass over the pulley 63, mounted upon the shaft 64, thereupon to take up their horizontal lengths of travel. The travel of the 5 belts 38 over pulley 63 will clearly be understood when it is observed from Figs. 1 and 2 that the spike-belt 42 hereinafter described passes also over said pulley 63 but between the belts 38, the belt 42 being 0 guided over said pulley and spaced from the belts 38 as illustrated in Fig. 1 by means of two of the four ribs 65 carried by said pulley 63.

As best shown when Figs. 2 and 7 are 5 examined in connection with each other, and particularly when it is remembered that Fig. 7 discloses certain of the parts of Fig. 1 as they would be perspectively viewed in the direction of the arrow 46 of said Fig. 1, the supporting table 19 has a transverse terminal edge which underlies the pulley 51. An auxiliary feeding table 66 is here employed in connection with said table 19 in such a manner that the upper surface of 5 table 66 (Fig. 6) is slightly below the level of the upper surface of table 19 and that the edge 66' (Fig. 2) of said auxiliary table is in abutment against the transverse edge of table 19 above-mentioned. As perhaps best shown in Fig. 6, collateral reference being had to Figs. 2 and 5, auxiliary table 66 is a generally flat, elongated plate having a slot medially and longitudinally formed upon the upper surface thereof for the accommodation of the spike-belt 42, which belt after traversing the pulley 63, settles within the slot just mentioned and traverses said slot in the direction of the arrow 46 shown in Fig. 1 until said belt is enabled 0 to descend toward the pulley 41 as shown in Figs. 1, 5 and 7. The spike-belt thence passes over the several pulleys 67, 68, 69 and 70 all suspended beneath the table 66 and each adjustable to tighten or slacken the belt 42 as indicated. These pulleys 67, 68,

69 and 70 as well as the guiding instrumentalities 71 and 72, respectively associated with the pulleys 67 and 70, will be herein-after described more in detail. It will be observed from Figs. 1, 10 and 11 that the parallel belts 38 below said table 66 pass said pulleys 68, 69 and 70 without interference therewith, said belts 38 thence passing over the pulley 63, as perhaps best shown in Fig. 2, and running over the upper surface of table 66 and alongside spike-belt 42 as best disclosed in Figs. 2, 5, 6 and 7. Belts 38 (Figs. 2 and 6 particularly) are guided in their paths of travel over said table 66 by means of the rigid guide bars 73. It may here be stated that the function of spike-belt 42 in the present instance is to present with reference to the auxiliary table 66 a predeterminedly elongated length of effective feed between the limits of which feathers may be manually or otherwise forced into engagement with the U-shaped spikes or staples 74 carried here at regular intervals by the belt 42.

As best shown in Fig. 6, the quills of feathers lie between the upstanding branches of the staples 74, the flues of the feathers extending outwardly past said branches to lie over belts 38; it being desirable that during a transportation of the line of feathers by the belt 42 the portions of said feathers shall be arranged substantially horizontally, and this end is here readily made possible by the provision of the member 75 disclosed in Figs. 1 to 9 inclusive and also in Figs. 12 and 14. The portion of the member 75 which overlies belt 42 maintains said belt against material vertical displacement from the accommodating slot for said belt formed in auxiliary table 66; said member 75, it may 95 here be noted, being preferably formed of a resilient material or having a slight tendency to act in a resilient manner. When belt 42 commences as aforesaid to branch downwardly from the paths of travel of belts 38 (see Figs. 1, 5 and 7) toward pulley 41, the staples 74 gradually descend with the belt 42 in accordance with the disclosure of said figures until, completely entering the undercut inclined slot 76 formed in table 19 (Fig. 5), said staples entirely disengage themselves from the line of feathers at a predetermined instant just following the instant when said line of feathers becomes gripped between belts 40 and 38 underneath pulley 51, up to which occurrence the staples 74 have effectually served the purpose of maintaining the feathers comprising the line of material in the identical relative dispositions which they occupied upon 100 their initial engagements with staples 74. The just-described operation may perhaps be better understood from an examination of Fig. 7, which it may still be remembered, shows certain of the parts disclosed in Figs. 130

1 and 5, were they observed in the direction of the arrow 46 of Fig. 2; in said Fig. 7 the belt 42 being shown traveling in the direction of its adjacent arrow and the belts 38 5 and 40 being shown traveling in the direction of their respectively adjacent arrows. The member 75 will be described in detail hereinafter.

Referring now particularly to Figs. 1, 2 10 and 3, Fig. 3 being merely a slightly enlarged view of the left-hand end of Fig. 2, it will be seen that on either side of table 66 is what may be termed an auxiliary work-bench 76, each work-bench having two semi-circular segments removed therefrom as indicated whereby an operator may be seated or disposed within each of the spaces 77. These operators may each thus have a suitable space, for the sorting, arrangement, &c., 15 of a supply of feathers or the like, available at his right-hand. Slightly ahead of the position of each feeder, the expressions being used with reference to the direction of travel of belt 42, there is located a bracket 78, 20 fixedly mounted upon table 66 and carrying a clamping-block which overlies the line of feed of belt 42 as disclosed. Each block is adapted to mount upon its supporting bracket an obliquely extending, preferably 25 resilient presser-finger 79, which extends downwardly to enter between the two substantially parallel lines of spikes established by the succession of staples 74. A portion of one of these presser-fingers with reference 30 to members 75, and with reference to an assumed presence of a line of material overlying said member 75 and being transported by spike-belt 42, is perhaps best disclosed in Fig. 7. The function of these 35 presser fingers is to completely press down upon the surface of member 75 those feathers which the operators may have fed to staples 74 but may not have pushed fully down against belt 42.

40 The construction of member 75 may now be described. The said member is in the main an elongated, preferably resilient bar of the cross-section shown in Fig. 6. The terminus of said bar adjacent pulley 63 is formed as best shown at the right-hand end 45 of Fig. 1 and at the left-hand end of Fig. 7, to the end that the curved undersurface of said bar may overlie the upper surface of belt 42 between the staples 74 during a 50 fraction of the passage of said belt over said pulley 63. The blade-like member 75' (Fig. 7) which thus overlies a portion of pulley 63 is beveled upwardly from its lower-most edge 75'' (Fig. 7), to the end that the 55 upcoming staples may unerringly have all their branches separated so that one branch of each staple will advance with the belt 42 while being separated from the other branch of said staple by the elongated bar which in 60 the main constitutes member 75. Member 65

75 also carries an upwardly extending portion 79 which is fixedly attached to a fixed transverse supporting plate 80.

The elongated bar of member 75 is undercut adjacent the point 81 (Fig. 7; see also Fig. 5). This undercut conformation is provided in view of the following desiderata. First, the undersurface of said undercut portion should preferably be mounted directly upon the upper surface of table 19. Second, the undersurface of the said elongated bar of member 75 is preferably arranged on the table 66 at a lower level than the surface of the table 19 due to the facts (a) that, with reference to their passage over the table 66, the upper surfaces of belts 38 are preferably level with the upper surface of said main portion of the member 75 (see Figs. 5 and 6) and (b) that, with reference to their passage over the table 19, the upper surfaces of the belts are preferably at such a higher level than the upper surface of the troughed-part of member 75 which overlies said table 19 (Figs. 1, 14 and 12) that the quills of the feathers, as well as the binding cord 82 hereinafter mentioned, may be suitably accommodated with reference to the level of the mutually contacting surfaces of belts 38 and 40.

Continuing a description of the construction of member 75, and more particularly of the end portion thereof which is disclosed to the right of Fig. 7, it will be seen from said Fig. 7 and also from Figs. 8 and 9 that transversely of the member 75 is formed a vertical wall bounded by a horizontal line 83 and by an arcuate line which marks the termination of a rounded, preferably shallow trough 84 formed in the upper surface of member 75. It will be seen best from Figs. 7 and 8 that this trough is not of uniform width throughout its length, the member 75 as disclosed in said Figs. 7 and 8 being provided with a plurality of preferably sidewisely resilient fingers 85 separated from the portion of said member which lies between said fingers by the slots 86 and that what may be considered portions of member 75 in continuation of said fingers 85 aid in constituting a wider trough to the right of the line A—A of Fig. 7. As best shown in Fig. 5 this wide trough extends to terminate here as shown beneath the presser-foot 87; blending into an auxiliary trough-carrying plate 88. Plate 88 is preferably separably provided, rather than integrally with member 75, so that said plate only need be removed in case access to the interior of the casing be desired. The construction of the presser-foot itself may now be taken up. It will be best seen from Fig. 12 that a presser-foot proper of the usual type is here utilized. Longitudinally of its undersurface the same is grooved as best indicated in Fig. 5, the groove being preferably transversely

arched so that the said groove may co-operate with plate 88 and the adjacent end-portion of member 75 to establish a tube or tunnel for the guidance therethrough adjacent the sewing point of the feather-quills and cord 82; the feather-flues, it being understood, being gripped fast between belts 38 and 40.

A U-shaped plate 89, upwardly canted as shown, is rigidly carried by the presser-foot, and is preferably adapted to press strongly yet resiliently downward upon the passing belts 38 and 40, this pressure being due here both to the resilient nature of the material of which said plate is constructed as well as to the usual resilient mounting of the presser-foot itself. The belts 38 and 40 advancing intermittently as aforesaid, the usual upwardly-thrusting feed-plate of the sewing machine is removed; the presser-foot on the slate 88 being merely slotted in the vertical alinement (Fig. 5) desirable to enable the needle 48 to predeterminedly contact with the selected bobbin-means located within casing 20. While in Fig. 12 only the cord 82 is disclosed, an assumption of the presence beneath said cord and between belts 38 and 40 of a line of feathers as indicated in Fig. 14 will render understandable the manner in which the feathers are stitched and bound to the cord to establish the predeterminedly continuous boa or the like; for it will be clear that the needle 48, in accordance with the design of the well-known type of sewing machine preferably employed, first descends to one side of the cord 82 (as indicated in full lines in Fig. 12) and next descends to the other side of said cord (as indicated in broken lines in Fig. 12), thereby to create the zig-zag stitch indicated in broken lines in said Fig. 12 at 90.

While it is obviously rather plain sailing for the stitched boa past the plate 88, except perhaps with relation to the final exit without damage of the boa from the apparatus (the operation of the means for which exit will be hereinafter explained), it is desirable that the transportation of the line of feathers by means of belts 38 and 40 from the line A—A of Fig. 7 to or adjacent the up-canted edge of plate 89 (Fig. 12), without danger of a displacement of one feather with relation to another, shall be more certain than the assurance afforded by the fact that belts 38 and 40 are preferably in a stretched condition. In aid of this, there is here provided upon the presser-foot an auxiliary terminal-piece 91 as best shown in Fig. 12. In connection with this terminal-piece, and in terminal contact preferably therewith, is provided a suspended inverted trough 92 as shown in Figs. 1, 2 and 4 (see also Figs. 13 and 14, and Fig. 7). This trough is adjustably hung from the hanger 93 as disclosed, and the hanger is mounted

upon table 19 by means of the bracket 94, carried by the horizontal, transverse bars 95. Adjacent each terminus of each bar 95 is a vertical slot for the reciprocal accommodation in each slot as shown of a rod 96, rods 70 96 supporting the presser-blocks 97 in forced vertical thrust against belts 38 and 40, due to the provision of the expansile springs 98 one of each which is coiled about one of each of rods 96.

The better to guide the completed boa toward the exit-means, here including the rollers 43 and 49 (Figs. 1 and 15), so that the thicker center-portion of the boa will be directed to enter the annular groove 53 of roller 39, a trough-member 99 (Fig. 5) similar to that portion of member 75 illustrated in Fig. 12 is here provided as disclosed. And coöperating with this member 99 is a member 100 carrying in its under-surface an inverted trough as best shown in Fig. 5. Member 99 is suspended from a cross-bar 101, said cross-bar also carrying two suspended guide-blocks 102 for the belts 38 and 40 (Fig. 4) and itself being adjustably mounted upon the bosses 103 (Figs. 1 and 4). The manner of feeding the cord 82 may now be traced. The cord is here led from the reel 104 (Figs. 1 and 4) to the wire-coil 105 (Fig. 1), thence through the arcuate slot 106 formed in the fixture 55, thence past a suitable pulley or the like beyond said slot in such manner that said cord advances preferably toward the annular groove 53 as shown in Fig. 3, thence around said pulley in the direction of the arrow 45 of Fig. 1, thence over the line of feathers that (Figs. 1, 5 and 7) is becoming disengaged from the staples 74 at the instant when said line is being drawn between the contacting surfaces of belts 38 and 40, thence under the inverted trough 92 (Fig. 14), thence under the presser-foot (Fig. 12), thence—and hereafter as a component part of the built-up boa—under the member 100, thence toward the annular groove 53' (Fig. 15), thence around said groove in a clock-wise direction, and thence around the periphery of roller 43 in an anti-clockwise direction. The reel 104 is here revolvably mounted as shown, and has associated therewith in the present instance a usual type of friction-means 107 adjustable predeterminedly to place a slight draft upon cord 82.

The travel of spike-belt 42 in the direction of arrow 46 (Fig. 1) is as aforesaid over the groove formed between ribs 65 on pulley 63 (Fig. 2), thence under member 75, but with the staples 74 upstanding beyond the upper surface of said member (Figs. 1, 6 and 7), thence gradually descending from association with said member (Figs. 1, 5 and 7), and thence to pass over the pulleys 41, 67, 68, 69 and 70 (Fig. 1).

Fig. 1 at once illustrates the here common

features of pulleys 69, 68 and 41. From Fig. 1 it will be seen that while the staples 74 are arranged to radiate from the peripheries of the pulleys above-mentioned, they 5 are directed inwardly toward the centers of pulleys 67 and 70. These last situations are taken care of here by the construction best shown in Figs. 1 and 10; Fig. 10 illustrating at once the here common features of pulleys 67 and 70 and of the guiding instrumentalities 71 and 72. From this Fig. 10 it will be observed that said pulleys 67 and 70 are each substantially merely disk-like wheels over whose smooth peripheries passes 10 the median portion of spike-belt 42 which lies between the upstanding branches of its line of staples 74. The function of guiding instrumentalities 71 and 72, each preferably adjustable with reference to the periphery of its adjacent pulley as shown, is to prevent any staple 74 from becoming entangled with or distorted or bent by the pulley 67 or 70 over which it is being transported; each of said instrumentalities 71 15 and 72 in the present embodiment being constructed as shown in Figs. 1 and 10.

The operation of this embodiment of the invention, which should, by the foregoing description, largely be obvious, is substantially as follows:—As many operators may be employed as desired, such that, for instance, certain of the spaces 77 (Fig. 2) may be unoccupied or additional spaces 77 or the like may be provided. It is desirable to 20 have the belt 42 advance as rapidly as possible and consistent with good "piling" by the operators, it being remembered that through the connecting instrumentalities above described the said belt 42, belts 38 and 25 40 are preferably driven intermittently and also uniformly. Thus, in accordance with the number of operators utilized and with the average of skill of the said operators calculated, the said belts are driven at an 30 appropriate predetermined speed to attain 35 the best results. It is the duty of each operator to lay upon the line of staples 74 which is passing his space 77 a predetermined number of feathers, each operator thus feeding 40 preferably simultaneously, to the end that when the portion of the belt 42 which has passed in sequence all of the operators employed and is proceeding beyond the operator nearest the pulley 51, said portion 45 will support a predetermined thickness of feather material. As aforesaid, the presser-fingers 79 serve the useful function of "padding down" the feathers fed to and being transported by belt 42. In the intermittent 50 feed of the belts 42, 38 and 40 in the direction of the arrow 46, the line of feathers will be carried beneath the horizontal course of the upper belts 40; the quills will be finally aligned by the untilted branches of staples 74 55 as said staples as aforesaid descend with the

belt 42 toward pulley 41 and said quills will be advanced underneath the groove 53 and the cord 83 (Fig. 3) to enter the tunnel or tube established above a portion of member 75 which lies on table 19 and under the 70 trough 92 (Figs. 5 and 14), and the flues of the feathers will be gripped fast between the opposed members of the two pairs of belts 38 and 40 and fixedly carried along with them to maintain the just-described alignment of the quills. On passing finally beyond the trough 92, the line of material is guided underneath the arched-trough of the presser-foot (Figs. 5 and 12). While the line is advancing a step the needle is up, 80 and during the pauses in such intermittent advance the needle descends, alternately on one and the other side of the cord 82 (Fig. 12), puncturing the feathers on the opposite sides of the superposed cord, and co-operating with other parts of the sewing machine which are operative below the feathers, to stitch the feathers together by the well-known zig-zag stitch as indicated at 90 in Fig. 12. Referring now particularly to Figs. 90 1, 4 and 5, thence the line of feathers is conveyed, incidentally passing over the trough-plate 99 and under the suspended-plate 100, until it makes egress between belts 38 and 40 by entering the annular groove 53' (Fig. 95 15) formed on pulley 39.

Attention is called to the important fact that before the boat is by the action of rollers 43 and 49 deflected from adjacency with belts 40, it has been entirely removed from any contact between belts 40 and 38 or with belts 38 at all, thus preventing any possibility that the action of rollers 43 and 49 will cause an accidental or other injury to the delicate flues of the feathers then being gripped between said belts 38 and 40. It should also be noted that when once a line of cord 82 has been run through the machine, to continue until almost exhausted in length, the new length will merely have 10 to be knotted to the end of the preceding cord in order to continue the proper operation of the machine. The importance of maintaining the horizontally spaced relation between the belts, especially adjacent the 11 field of operations of the sewing machine will be appreciated, which end is attained here by the provision of the portion of member 75 which lies upon table 19, the plate 88, the plate 99, the parts carried by the cross-piece 101, the spacing-blocks 59, and the various ribs carried as shown by the pulleys which guide said belts 38 and 40; as well as the necessity for keeping the binding cord 82 in proper tension and properly aligned so 12 that the danger of the needle piercing the cord or plate is avoided, which end is accomplished here by the tension-device 107, the predeterminedly driven rollers 43 and 49, the spring mounting 50 of the roller 49, 13

and the annular groove 53' carried by the roller 39.

I claim:

1. In apparatus of the class described, in combination, a sewing means, conveying means for transporting a line of feathers past said sewing means; a translatable carrier movable toward said conveying means and including a plurality of substantially parallel series of spikes longitudinally arranged on the carrier, and a rod-like member lying over the median longitudinal portion of said carrier and between said series of spikes, said spikes projecting above the upper surface of said member. 70
2. In apparatus of the class described, in combination, a sewing means, conveying means for transporting a line of feathers past said sewing means; a translatable carrier movable toward said conveying means and including a plurality of substantially parallel series of spikes longitudinally arranged on the carrier, and a rod-like member lying over the median longitudinal portion of said carrier and between said series of spikes, said spikes projecting above the upper surface of said member; and a resilient member which extends downwardly toward said rod-like member. 75
3. In apparatus of the class described, in combination, a sewing means, conveying means for transporting a line of feathers past said sewing means; a translatable carrier movable toward said conveying means and including a plurality of substantially parallel series of spikes longitudinally arranged on the carrier, and a rod-like member lying over the median longitudinal portion of said carrier and between said series of spikes, said spikes projecting above the upper surface of said member; said rod-like member being fixed relatively of said translatable carrier and serving to support the quills of feathers the flues of which are engaged by said spikes. 80
4. In apparatus of the class described, in combination, a sewing means, conveying means for transporting a line of feathers past said sewing means; a translatable carrier movable toward said conveying means and including a plurality of substantially parallel series of spikes longitudinally arranged on the carrier, and a rod-like member lying over the median longitudinal portion of said carrier and between said series of spikes, said spikes projecting above the upper surface of said member; said member terminating adjacent said conveying means in a trough-like portion. 85
5. In apparatus of the class described, in combination, a sewing means, conveying means for transporting a line of feathers past said sewing means; a translatable carrier movable toward said conveying means and including a plurality of substantially parallel series of spikes longitudinally arranged on the carrier, and a rod-like member lying over the median longitudinal portion of said carrier and between said series of spikes, said spikes projecting above the upper surface of said member; said member terminating adjacent said conveying means in a trough-like portion which lies in the longitudinal space between said conveying means. 90
6. In apparatus of the class described, in combination, a sewing means, a plurality of conveying means for transporting a line of feathers past said sewing means, one of said plurality passing to one side of said sewing means and the other passing to the other side of said sewing means whereby in advance of said sewing means there is provided a longitudinal space between said conveying means for the accommodation of the quills of the feathers, an endless belt movable toward said conveying means and including a plurality of substantially parallel series of spikes longitudinally arranged on the belt, and a rod-like member lying over the median longitudinal portion of said carrier and between said series of spikes, said spikes projecting above the upper surface of said member. 95
7. In apparatus of the class described, in combination, a sewing means, a plurality of conveying means for transporting a line of feathers past said sewing means, one means of said plurality passing to one side of said sewing means and the other passing to the other side of said sewing means whereby in advance of said sewing means there is provided a longitudinal space between said conveying means for the accommodation of the quills of the feathers, an endless belt movable toward said conveying means and including a plurality of substantially parallel series of spikes longitudinally arranged on the belt, and a rod-like member lying over the median longitudinal portion of said carrier and between said series of spikes, said spikes projecting above the upper surface of said member; said member terminating adjacent said conveying means in a trough-like portion which lies in the longitudinal space between said conveying means. 100
8. In apparatus of the class described, in combination, an endless belt carrying a plurality of substantially parallel series of spikes longitudinally arranged on the belt, a plurality of guiding instrumentalities over which the belt passes whereby a portion of said belt traverses a substantially horizontal course, and a rod-like member overlying the median longitudinal portion of 105
9. In apparatus of the class described, in combination, a sewing means, conveying means for transporting a line of feathers past said sewing means; a translatable carrier movable toward said conveying means and including a plurality of substantially parallel series of spikes longitudinally arranged on the carrier, and a rod-like member lying over the median longitudinal portion of said carrier and between said series of spikes, said spikes projecting above the upper surface of said member; said member terminating adjacent said conveying means in a trough-like portion which lies in the longitudinal space between said conveying means. 110
10. In apparatus of the class described, in combination, a sewing means, conveying means for transporting a line of feathers past said sewing means; a translatable carrier movable toward said conveying means and including a plurality of substantially parallel series of spikes longitudinally arranged on the carrier, and a rod-like member lying over the median longitudinal portion of said carrier and between said series of spikes, said spikes projecting above the upper surface of said member; said member terminating adjacent said conveying means in a trough-like portion which lies in the longitudinal space between said conveying means. 115
11. In apparatus of the class described, in combination, a sewing means, conveying means for transporting a line of feathers past said sewing means; a translatable carrier movable toward said conveying means and including a plurality of substantially parallel series of spikes longitudinally arranged on the carrier, and a rod-like member lying over the median longitudinal portion of said carrier and between said series of spikes, said spikes projecting above the upper surface of said member; said member terminating adjacent said conveying means in a trough-like portion which lies in the longitudinal space between said conveying means. 120
12. In apparatus of the class described, in combination, an endless belt carrying a plurality of substantially parallel series of spikes longitudinally arranged on the belt, a plurality of guiding instrumentalities over which the belt passes whereby a portion of said belt traverses a substantially horizontal course, and a rod-like member overlying the median longitudinal portion of 125
13. In apparatus of the class described, in combination, a sewing means, conveying means for transporting a line of feathers past said sewing means; a translatable carrier movable toward said conveying means and including a plurality of substantially parallel series of spikes longitudinally arranged on the carrier, and a rod-like member lying over the median longitudinal portion of said carrier and between said series of spikes, said spikes projecting above the upper surface of said member; said member terminating adjacent said conveying means in a trough-like portion which lies in the longitudinal space between said conveying means. 130

said belt and between said series of spikes, said spikes projecting above the upper surface of said member, said rod-like member having a terminal portion adjacent one terminus of said horizontal course which is provided with a depending portion that guides said series of spikes to pass one on each side of said rod-like member, said depending portion bearing against said belt

while the same is passing over one of said 10 guiding instrumentalities.

In witness whereof I have hereunto signed my name in the presence of two witnesses.

CHARLES L. KAUFMAN.
